UNITED STATES PATENT OFFICE.

GEORGE C. HENNING, OF WASHINGTON, DISTRICT OF COLUMBIA.

LABEL.

SPECIFICATION forming part of Letters Patent No. 334,437, dated January 19, 1886.

Application filed January 30, 1885. Serial No. 154,493. (No model.)

To all whom it may concern:

Be it known that I, GEORGE C. HENNING, of Washington, in the District of Columbia, have invented certain new and useful Improvements in Labels, of which the following is a specification.

My invention relates to address cards or labels for the use of merchants and others, and is designed to facilitate the giving of directions to the porter or messenger.

The invention consists in a novel arrangement of words and devices whereby a simple stroke or mark of a pen or pencil gives the required information to the porter as to each of the several matters to which the directions relate.

Figure 1 represents the card or label in its preferred form complete; Figs. 2, 3, 4, 5, 6, and 7, views illustrating details and slight variations.

Hitherto address cards or labels have generally contained simply a number of blank spaces in which the necessary directions were required to be written out as fully as time and space would permit. Though the time and labor required to thus fill out the few directions embraced by such cards or labels were small in any single case, much time and labor were involved in preparing the large number of cards required by mercantile houses doing a large business, and even then the comparatively small size of the card and the time required to read the directions prevented the giving of such full instructions as experience shows to be desirable.

My invention is designed to obviate these difficulties, to permit a large amount of information to be plainly given in small compass, and to enable a clerk to fill out and a porter or messenger to read the directions quickly and with certainty. With these objects in view the label or card contains one or more lines, *a*, for the name of the person to whom the package is to be sent, and for the name of the street and number of the house.

To enable the direction of the place or section of the city in which the house is located to be speedily indicated, and with certainty, I provide the card or label with an indicator, *b*, showing by radial lines the cardinal points of the compass—north, south, east, and west—

and also the intermediate points, northeast, southeast, southwest, and northwest. With this indicator a simple stroke of the pen or pencil opposite or across the proper line will indicate at a glance, and even to an ignorant person, the direction of the place to which the parcel is to go, giving an idea of the location by the position of the line in the figure, as well as by the designation printed on such line. This indicator is preferably placed at the end of the lines provided for the name of the person and street.

It is commonly desirable that packages be delivered at, before, or after a stated time, and on a given day, and to quickly designate and clearly indicate the hour and day, I provide one or more circular rows or lines, *c d*, of figures, from 1 to 12, or from 1 to 24, as preferred, and blanks *e f g* for the year, month, and day, thus: "18...., ...month, ...day."

The arrangement of the figures may be varied considerably without affecting their use, the preferred arrangement being that shown in Fig. 1, in which two concentric rows or circles containing figures from 1 to 12 and from 13 to 24, respectively, are used. To indicate the hour of the day it is then only necessary to mark any figure required, instead of writing out the instructions in full, the indications "A. M." and "P. M." being rendered unnecessary by the use of the twenty-four divisions consecutively numbered.

It frequently happens that instructions are given to deliver before or after a designated hour, and to give the necessary directions in such case I provide the two circles *c d*, above mentioned, and print in or by them, respectively, the words "deliver after" and "deliver before."

The blanks *e f g* are filled in the usual way—as, for instance, "1885, 1st month, 30th day."

Instead of the two concentric rows of figures running jointly from 1 to 24, each may contain figures from 1 to 11, the twelfth space being occupied in one row or circle by the letters "A. M." and in the other by the letters "P. M." as in the left-hand circle of Fig. 3, or a single row of figures may be used from 1 to 11, as in Fig. 2, with the letters "P. M." and

A. M.," respectively, inside, and outside of the circle at a point between the figures indicating 1 and 11.

So, too, the single row or circle of figures 1 to 12 may be used, as in the right-hand circle of Fig. 3, the letters "A. M." and "P. M." being placed above and below the figures indicating 12, or a single circle of figures indicating hours from 1 to 24 may be adopted, as in Fig. 4. Finally, instead of arranging the figures in the circles, they may be arranged in straight lines, as in Figs. 5, 6, and 7, either in two rows from 1 to 12 each, or in one or more rows from 1 to 24. If in two rows, each containing figures indicating hours from 1 to 12, the letters "A. M." and "P. M." will be used, as indicated. The circular arrangement is preferred for the reason that the resemblance to a clock-dial thus secured enables the hour to be more readily noted and with greater certainty than when the figures are differently arranged.

To provide for the delivery of parcels or packages to depots, stations, or wharves at proper time for shipment, or at such time as will insure their arrival at their destination by a stated time, I provide a similar arrangement of circles, *h i*, and blanks *j k l*, the circles bearing, respectively, the words "train leaves" and "boat leaves."

Besides the matters mentioned, the card or label bears the words "Sold by;" "Examine;" "Collect;" "Exchange;" "Take Chk.;" "Leave;" "Exchange;" "Paid;" "Carriage paid;" each within a separate space containing additional room sufficient to receive an arbitrary mark of any kind to give the porter or messenger the required information. For instance, the space containing the words "Sold by" may be marked with a letter, figure, or other arbitrary symbol recognized in the store or establishment as the mark of a certain employee. The space bearing the query "Collect" will be filled in with the amount to be collected, or left blank, as circumstances require, and so as to the remaining spaces, if not marked, they may be understood to require no consideration. This plan gives the information only to those knowing the rule of the house sending the parcel. The wording may of course be varied as the particular line of business requires; but the important point of arranging the instructions in the manner indicated, so that a single arbitrary mark shall convey the required information to the porter or messenger without imparting the same to the purchaser or others, should be followed in all cases.

Any further instructions and any suitable advertising matter may of course be combined

with the foregoing; but the above includes the matter which I deem novel and of special importance.

With the card thus arranged, it is necessary only to write out the name of the person, name 65 of street, and number of house. All the rest may be filled in or indicated by a simple pen-stroke, with the exception of the date and amount to be collected, if any, which may be quickly done by a few figures. 70

I am aware that a notched dial provided with figures indicating hours has been combined with a spring-locking device and pointer and attached to a clasp for application to boots and shoes and like articles, to indicate 75 the hour at which said articles were to be returned to the owner's apartment. This I do not claim.

My label is designed to be printed on paper, and to be thrown away after being once used. 80 The particular hour to be indicated is crossed or marked out by a pen or pencil stroke, and the necessity of a pointer, catch, or like device is obviated.

Having thus described my invention, what I 85 claim is—

1. A card or label provided with space for the name and general address, and with an indicator showing the points of the compass, whereon may be designated the general direction or section of the city, substantially as described, and adapted to be marked by a simple pen-stroke to indicate the particular direction required. 90

2. A label provided with a space for an address, and with figures indicating the hours of the day, both printed or produced directly thereon, whereby a simple pen or pencil mark may be made to designate the time at, after, or before which a parcel is to be delivered to 100 the address written on the card. 95

3. An address card or label provided with a series of questions adapted to be marked to constitute directions, as explained, whereby the necessary information may be given to a 105 porter or other person without being disclosed to a purchaser.

4. The herein-described card or label provided with space *a* for the general address, indicator *b*, adapted, when marked, to indicate the 110 general direction, circles *c d h i*, bearing figures indicating hours of the day, and instructions as to delivery of goods, spaces *e f g j k l*, to receive indications as to dates, and a series of instructions in the form of questions, all substantially as set forth and shown. 115
